UNITED STATES PATENT OFFICE.

GEORGE P. KINGSEURY, OF BROOKLYN, NEW YORK, ASSIGNEE TO MERGENTHALER LINOTYPE COMPANY, A CORPORATION OF NEW YORK.

TYPOGRAPHICAL CASTING-MACHINE.

1,119,519.

Specification of Letters Patent.

Patented Dec. 1, 1914.

Application filed November 10, 1913. Serial No. 800,025.

To all whom it may concern:

Be it known that I, GEORGE P. KINGSEURY, a citizen of the United States, residing at Brooklyn, in the county of Kings and State of New York, have invented certain new and useful Improvements in Typographical Casting-Machines, of which the following is a specification, reference being had thereto to the accompanying drawing.

10 My invention relates to typographical machines, such as linotype machines of the general organization represented in Letters Patent of the United States, No. 436,532, to O. Mergenthaler, wherein circulating matrices are released from a magazine in the order in which their characters are to appear in print and then assembled in line, the composed line transferred to the face of a mold, the mold filled with molten metal 15 to form a slug or linotype against the matrices which produce the type characters thereon, and the matrices thereafter returned through distributing mechanism to the magazine from which they started.

20 More particularly, it relates to the ejecting means which advance against the edge of the cast slug or bar and deliver it from the mold.

In many of the machines known in the art, the mold is variable or adjustable in length, in order to produce slugs for printing columns or pages of different widths; and in connection with such adjustable mold is frequently employed a composite ejector 35 having its parts so constructed and combined that its operative portion may be varied in width to correspond with changes in the length of the mold slot. As illustrated for instance in Letters Patent of the 40 United States, No. 967,976, to John R. Rogers, the ejector blade is composed of a series of parallel sections arranged edge to edge, and mechanism is provided whereby any desired number of these sections can be 45 connected with the actuating slide, while the others are left free therefrom.

In contradistinction to the composite ejector just described, it is the purpose of the present invention to employ a plurality 50 of individual ejector blades of different widths, and means for rendering any one of said blades active at will. Preferably and specifically, these blades are arranged side by side and are movable laterally so that the 55 selected one may be brought into operative

relation to the actuating slide. The specific construction of my improvements will be described in the following specification, and the invention itself finally pointed out in the claims.

60 In the accompanying drawings, I have shown my invention in preferred form and by way of example, and as applied to the kind of machine already mentioned, but obviously many changes and variations may be made therein, and in its mode of application, which will still be comprised within its spirit; and it may be applied to other forms of typographical machines, such as typecasters and the like, which produce type 65 or matrices, instead of slugs or bars. Generally speaking, I desire it to be understood that I do not limit myself to any specific form of embodiment, except in so far as such limitations are specified in the claims.

70 Referring to the drawings: Figure 1 is a central vertical section through the mold slide and adjacent parts of a linotype machine having my invention applied thereto; Fig. 2 is a horizontal section on the line 75 2-2 of Fig. 1; Fig. 3 is a vertical section on the line 3-3 of Fig. 1; Fig. 4 is a vertical section on the line 4-4 of Fig. 2; and Fig. 5 is a detail perspective of a single ejector blade, the actuating slide, etc.

75 The mold A is mounted as usual in the mold carrier or disk A¹, and the ejector blade B acts against the edge of the slug or linotype cast therein and delivers it therefrom between the knives C¹, from which it 80 passes to the galley. The blade B is connected to and actuated by the ejector slide C mounted in the mold slide D, the slide C being reciprocated by the link E, lever F, and ejector cam G. The parts so far described, 85 and their mode of operation, are or may be similar to those known in the art, and except as hereinafter described, their particular form constitutes no part of the present invention. Also connected to the lever F 100 is the arm K, rod J, and treadle lever H, whereby the blade B may be removed at the will of the operator from its normal position in the mold, to permit a change in the width of the blade, or for other purposes, 105 these parts being substantially similar to those disclosed in my application for Letters Patent, Serial No. 732,805, filed March 8, 1913.

110 As previously set forth, and as distin-

guished from the composite ejector blade made up from a series of individual sections arranged edge to edge, disclosed in the said Rogers patent. It is my purpose to employ a plurality of individual blades B of different size or width, any one of which may be brought into operative relation to the ejector slide C. Preferably the several blades B are arranged side by side and mounted in a box or frame L, which is carried by and laterally adjustable with reference to the mold slide D, as for instance upon the rods D¹ supported by the slide. The supporting frame L is shown as formed with guideways for the several blades, such as the oppositely located longitudinal grooves L¹, adapted at one side of the frame to receive the edges of the blades, and at the opposite side the edges of the offset portions B² thereof, the portions B² being of uniform size irrespective of the width of the blade connected thereto. This construction permits the individual actuation of the selected blade by the slide C without effect upon the other or inactive blades.

The frame L is so located in the mold slide D, and the blades B are so disposed in the frame, that the transverse adjustment of the frame moves the blades one after another into operative relation to the slide C, when the latter is in its rearward or retracted position. As best shown in Fig. 5, the offset portions B² of the blades are formed with mortises B³ adapted to engage corresponding tenons C² on the slide C, so that as any selected blade is brought into position it will be firmly engaged by and locked to the actuating devices. The slide C is also formed with laterally projecting shoulders or flanges C¹, so that when the slide is advanced through the frame L, these shoulders will pass into the grooves L¹ of the frame, which arrangement not only permits the free actuation of the blades, but due to the engagement of the shoulders with the grooves, also holds the frame against lateral adjustment until the slide C is entirely retracted and arrested, as for instance by the abutment of the shoulders C¹ against the studs or stops D² upon the mold slide D. It will be noted that only at this time are the mortises B³ brought into registration with the tenons C², to permit the disconnection of the active blade and the subsequent connection of a blade of different width.

The means for adjusting the box or frame L laterally, so as to bring one or another of the blades carried thereby into action, may be of any desired character. In the drawings they are specifically shown as comprising an extension L² from the frame, the arm M connected thereto and mounted on the rock shaft N, and the adjusting arm O also mounted on the rock shaft, and provided with the hand piece or button O¹ to

facilitate the manual adjustment of the parts. The arm O also carries a spring-pressed pin or detent O² adapted to engage the toothed sector P, the latter being provided with a suitable scale to indicate the various widths of blades and to permit the selection of an appropriate one.

As previously stated, I have shown my invention only in preferred form and by way of example, and as adapted to a particular form of machine; but obviously many modifications and alterations therein, and in its mode of application, will suggest themselves to those skilled in the art, without departure from its scope.

Having thus described my invention, its construction and mode of operation, what I claim and desire to secure by Letters Patent of the United States, is as follows:

1. An ejector mechanism comprising, in combination, a series of ejector blades, and a supporting frame therefor movable to bring one or another of said blades into operative position, the said frame being formed with two opposing series of grooves located in parallel planes and wherein the blades are slidably arranged.

2. An ejector mechanism comprising, in combination, a series of ejector blades of different widths, and a movable supporting frame formed with sets of opposing grooves wherein the blades are slidably arranged, the said blades being formed with offset portions to engage in the upper grooves of said sets, and the said offset portions being of uniform width on all the blades to permit such engagement irrespective of the width of the blades.

3. An ejector mechanism comprising, in combination, a series of ejector blades of different widths, and a movable supporting frame wherein the blades are slidably arranged, said blades being formed with offset guiding portions which are of uniform width on all the blades, for the purpose described.

4. An ejector mechanism comprising a series of ejector blades of different widths and formed with the offset portions B², the said portions being of uniform width on all the blades, for the purpose described.

5. An ejector mechanism comprising, in combination, a reciprocating actuating device, a series of ejector blades, and a supporting frame therefor movable to connect one or another of the blades with the actuating device, the said frame being formed with grooves wherein the blades are slidably arranged, and the said actuating device being formed with flanges O¹ to engage in said grooves during its reciprocations.

6. An ejector mechanism comprising, in combination, a series of ejector blades of different widths, and a movable supporting frame comprising a top plate formed with

a series of grooves, the said blades being formed with offset guiding portions to engage in said grooves.

7. An ejector mechanism for typographical machines comprising, in combination, a series of ejector blades, a movable supporting frame therefor formed with a series of grooves wherein the blades are slidably arranged, and an actuating device adapted to 10 be connected to one or another of the blades and formed so as to engage in and be guided by the corresponding groove during its actuating movement.

8. An ejector mechanism for typographical machines comprising, in combination, a series of ejector blades, a frame therefor movable to bring one or another of the blades into operative position, an actuating device connected to the operative blade and standing normally within the frame, and means for withdrawing the device from the frame to permit the movement of the latter.

9. An ejector mechanism for typographical machines comprising, in combination, 25 a series of ejector blades movable as a whole to bring one or another into operative position, the operative blade standing normally out of alignment with the remaining blades, an actuating device connected to the operative blade, and means for withdrawing the device to align the operative blade with the others and thus permit their movement to effect the connection of a different blade to the actuating device.

10. An ejector mechanism for typographical machines comprising, in combination, a series of ejector blades of different sizes, the active one of which stands normally out of alignment with the remaining ones, a supporting frame for the blades movable to bring a different blade into operative position, and means for preventing the movement of the frame until the active blade has been aligned with the other blades.

11. In a typographical machine, the combination of a mold, a series of ejector blades of different sizes, the active one of which stands normally within the mold, a supporting frame for the blades movable to bring a different one into operative position, and means for preventing the movement of the frame until the active blade has been withdrawn from the mold.

12. An ejector mechanism for typographical machines comprising, in combination, 55 an actuating device, a series of ejector blades of different sizes movably arranged so that any selected one may be connected to the actuating device, and means for preventing the movement of the blades until 60 the actuating device has been moved from its normal position of rest.

In testimony whereof I have affixed my signature in presence of two witnesses.

GEORGE P. KINGSBURY.
